DUAL RADIANT HEATER

Maxwell K. Murphy, 535 W. Goldengate, Detroit, Mich.
Filed Apr. 20, 1959, Ser. No. 807,355
7 Claims. (Cl. 219—39)

This invention relates to electric heating devices and particularly to a wall mounted combined convection and radiant heater for heating two rooms simultaneously.

The advantages of heating by radiation alone are well known. Most radiant heating systems, however, are slow in response when first energized; and in panel installations for zone heating in climates where the heating unit may be completely "off" for most of the day, user complaints are common. Furthermore, it appears that a forced current of warmed convection air satisfies a physiological demand on the part of most people which radiant heat does not meet, at least during the initial warmup period.

Electric radiant heaters of the glass or porcelainized sheet type have proven exceptionally satisfactory for panel type heating because of their excellent radiating capacity and economy. These sheet type elements provide considerable radiation or leakage from the back side, which emitted heat is usually reflected toward the element by a metal reflector to increase radiating efficiency.

It is the object of my invention to provide an improved dual combined radiant and convection heater utilizing sheet type elements which is suitable for heating two rooms of a house with economy of construction and operation, and economy of wall space.

For a preferred embodiment of my invention, reference is made to the accompanying drawings, in which reference characters have been used to designate like parts referred to herein.

In the drawings:

FIG. 1 is a front elevation of my dual heater, the rear elevation being an exact duplicate;

FIG. 2 is an enlarged vertical section taken as indicated by the line 2—2 on FIG. 1;

FIG. 3 is an enlarged fragmentary section of one of the heating elements taken on line 3—3 of FIG. 1; and

FIG. 4 is a schematic wiring diagram of the heater control circuit.

Referring to the drawings, it may be seen that my improved heater comprises a casing 10 of metal, Fiberglas or the like. The casing has oppositely disposed sidewalls, top and bottom walls as shown, and front and back walls provided with large area openings for reception of the heating elements 12, 14.

Oppositely disposed air intake conduits 16, 18 are disposed at the top of the assembly, and at the bottom the casing is provided with oppositely facing air outlet registers 20, 22. The latter are provided with movable vanes or shutters which are adjustable by knobs 24, 26, so that one or the other may be closed when desired.

The entire assembly is of such width—approximately 15 inches—that it will fit between the joists of a building, which joists are usually spaced 16 inches apart in accordance with standard building codes.

The assembly is of such width that the heating elements 12, 14, will be substantially flush with oppositely facing wall surfaces of adjoining rooms of a house or building with the intakes 16, 18, and outlet registers 20, 22, protruding slightly.

The heating elements 12, 14, are of sheet form and are secured in the casing 10 in any suitable manner, such as flanges 28. The elements may be of the glass type, such as those widely sold under the trade name "Glassheat," or they may be of the porcelainized metal type. Referring to FIG. 3, it may be seen that the element 12 comprises a steel sheet 30 having a coating 36, 32, of vitreous material on each surface thereof. Adhered or fused to the

2

rear surface coating 34 is a resistor 36 of aluminum alloy or other metal. The latter is preferably in the form of a grid, and if desired, a protective coating of silicone varnish or other heat resistant material may be applied over the 5 resistor grid to inhibit corrosion.

For other examples of heating elements suitable for use in the device being described, reference is made to Glynn Patent Number 2,622,178, Garaway Patent Number 2,859,321, Knoll Patent Number 2,795,682, and to my 10 copending application Serial No. 715,604, filed February 17, 1958.

Application of a voltage across the resistor of the element will heat the element, and heat rays, most of which are in the infra-red range of the spectrum, will be radiated from the front surface of the element. The oppositely disposed rear surface of the other heating element will act as a reflector of heat rays emitted from the rear surfaces of the two elements and thus the radiating efficiency of the elements is increased.

While most of the heat generated will be radiated directly into the rooms in which the elements 12 and 14 face, there will be considerable heat emitted into the interior of the casing which heat, in the absence of any air propelling means, will flow out of the heater intakes 16 25 and 18 through the chimney effect produced by air entering the registers 20, 22, and help heat the space by convection.

Because heat tends to rise and to increase the overall heating efficiency of the device, I prefer to admit air to 30 the interior of the casing behind the heating elements at the top and to force the heated air out at the bottom. To accomplish this, a blower assembly is provided which comprises a motor 38 and a bladed rotor 40. At the bottom, baffles 42, 44, are disposed such that air drawn in at 35 the top through intakes 16, 18, will be heated and expelled through the registers 20, 22, at the bottom. The intensity of the air current may be reduced in one room and correspondingly increased in the other by proper adjustment of the register louvres by means of knobs 24, 26. In some 40 instances, where one of the rooms is relatively small (a bathroom, for example), the baffles 42, 44, may be disposed eccentrically to provide a permanent unequal distribution of convection heat.

In the operation of the heater, it is preferable that a 45 thermostat be used to control the on and off cycle of the elements. It is preferable that the thermostat be located remotely from the heater so that it will not be influenced by direct radiation or conduction therefrom, and the thermostat should be in the room most sensitive to 50 temperature changes.

The heater may be energized from a standard household 115, 208 or 240 volt line, and the elements and blower may be connected in parallel such that the blower 55 operates whenever the elements are energized to thereby provide a combination of radiant and convection heat.

From the standpoint of economy, it is preferable, however, that a differential type of thermostat be used which will energize the blower and the heater elements at some selected temperature, say 68° F., and when room temperature has risen to 70° or 72° F., the blower will cut out leaving the elements 12, 14, energized to continue heating by radiation until the temperature rises to some selected maximum, say 75° F., whereupon the elements 12, 14, will cycle on and off to maintain desired comfort by radiation alone. This system provides quick warmup of a cold room by a combination of convection and radiant heat, then continues to maintain comfortable temperature by radiation alone. Such a control system is described and claimed in my copending application Serial No. 771,70 604, filed November 3, 1958, now Patent No. 2,978,568, granted April 4, 1961.

The present arrangement is adapted to a different type

of control which greatly enhances the utility of the heater and improves the economy of operation thereof. Reference is made to FIG. 4 which shows a schematic circuit for controlling the heater.

In this arrangement, the heating elements 12 and 14 are fabricated for normal operation at (for example) 110 volts. The input circuit from the main supply is a three wire circuit with (for example) either 208 volts or 230 volts between outside conductors 46, 48. The voltage between conductors 46—50 and 48—50, is 110.

The differential thermostat 52 is connected in the secondary circuit of a transformer 54 and controls energization of relay coils 56, 58, which coils when energized, close switches 60, 62, respectively.

When the thermostat 52 calls for heat at low setting, it will energize relay coil 58 through leads 64, 66, 68, to close switch 62. Switch 60 remains open. Closure of switch 62 will energize elements 12, 14, through leads 46, 70 and 48, and thus subject the elements to the higher voltage existing across leads 46, 48. At the same time, motor 38 will be energized through leads 50, 72, 74 and 48. Application of overvoltage to the heating elements 12, 14, will provide extremely quick warmup of these elements with consequent rapid warming of the heated space by a combination of convection and radiation. Because the heating elements are designed for normal operation at lower voltage, the overvoltage will cause failure of the elements by burnout unless the heat is removed from the element with sufficient rapidity to prevent overheating of the resistor grids. This is readily accomplished by the blower 40, which of course must be chosen of sufficient capacity to perform this function.

As soon as the temperature of the heated spaces rises to preset minimum, thermostat 52 will de-energize coil 58 and energize coil 56. The blower will cease operation and the high voltage circuit to the heating elements will be opened. At the same time, switch 60 will close connecting elements 12, 14, to the low voltage supply through leads 50, 76, 78 and 46. The heater element, now thoroughly warm, will continue to heat by radiation with some convection currents flowing in reverse direction through the casing 10. When the thermostat 52 reaches its maximum setting, it will de-energize coil 56 and will continue to cycle this coil to maintain comfort unless there is a rapid drop in room temperature whereupon the coil 58 will be again energized.

By subjecting the heating elements to overvoltage, rapid warmup of the elements with consequent rapid warmup of the space is achieved. In addition, a blast of warm air is circulated in the space. This feature appears to nullify complaints of users with respect to slow response by electric radiant heaters, and seems to satisfy a physiological demand of persons who associate an adequate heating system with a blast of hot air.

Once the forced convection air has warmed up the space, the cycling of the heating elements at normal voltage with substantially total radiant emission will maintain comfort with excellent economy.

It will be thus seen that I have provided an improved heating appliance which supplies both convection and radiant heat to adjoining rooms with economy of construction and operation, and with extreme compactness and economy of wall space.

I claim:

1. In a combination radiant and convection heater adapted for installation in a common wall between adjacent rooms, a pair of sheet type electric radiant heating elements having resistor grids adhered to their respective inner surfaces mounted back-to-back in spaced relation for emitting heat rays from their respective outer surfaces directly into said rooms, a pair of oppositely disposed air inlets mounted above said heating elements, a pair of

oppositely disposed air outlets mounted below said heating elements, and a blower mounted in the heater operable to provide forced air circulation through said heater from said inlets and out through said outlets thereby to provide convection currents of heated air from the rear surfaces of said elements in both rooms.

2. The combination of claim 1 including a baffle mounted below said elements and adjacent said outlets for directing the air currents outwardly in opposite directions.

3. The combination of claim 1 including adjustable louver means in each outlet for varying the flow of air into each room.

4. The combination of claim 1 including heat responsive control means for controlling energization of said elements and said blower operable to energize said blower and simultaneously connect said heating elements across a relatively high voltage supply in response to selected temperature condition prevailing in said rooms, and to de-energize said blower and connect said elements across a lower voltage supply in response to attainment of a second temperature condition in said rooms.

5. In combination with a wall mounted heater for heating adjoining rooms simultaneously, a pair of electric radiant heating plates having resistor grids adhered to their respective inner surfaces, said plates being mounted in spaced oppositely facing relation with their respective heat emitting outer surfaces exposed to said rooms, means for withdrawing air from said rooms and for forcing said air through the space between said plates and out into said rooms thereby to provide forced convection heating of said rooms to augment the radiant emission from said plates.

6. In combination with a wall mounted heater for heating adjoining rooms simultaneously, a pair of electric radiant heating plates having resistor grids adhered to their respective inner surfaces, said plates being mounted in spaced oppositely facing relation with their radiating outer surfaces exposed to said rooms, means for forcing a current of air from said rooms through the space between said plates and out into said rooms thereby to provide forced convection heating of said rooms to augment the radiant emission from said plates, thermostat means for controlling said heater including means for simultaneously energizing said heating elements and said air current forcing means at selected temperature thereby to provide combination radiant and convection heating of said rooms, and means for cutting off operation of said forcing means at selected higher temperature thereby to provide radiant heating only.

7. The combination set forth in claim 6 wherein said heating elements are energized at higher than normal operating voltage during the period of combined radiant and convection heating.
